UNITED STATES PATENT OFFICE.

WILLIAM C. THOMAS, JAMES C. DICKENS, AND JESSE W. FOWLER, OF GOOSE CREEK,
TEXAS.

DEVICE FOR UNSCREWING AND WITHDRAWING PIPE.

1,389,710.

Specification of Letters Patent. Patented Sept. 6, 1921.

Application filed February 19, 1921. Serial No. 446,495.

To all whom it may concern:

Be it known that we, WILLIAM C. THOMAS, JAMES C. DICKENS, and JESSE W. FOWLER, citizens of the United States, residing at 5 Goose Creek, in the county of Harris and State of Texas, have invented certain new and useful Improvements in a Device for Unscrewing and Withdrawing Pipe, of which the following is a specification.

10. This invention relates to new and useful improvements in a device for unscrewing and withdrawing pipe.

One object of the invention is to provide a device of the character described specially 15 adapted for use in unscrewing and withdrawing pipe from a well bore.

Another object of the invention is to provide a device of the character which may be operated in either direction and which may be 20 readily brought into engagement with the joints of a pipe, stuck in a well bore, to unscrew and withdraw them singly therefrom.

With the above and other objects in view this invention has particular relation to certain 25 novel features of construction, operation and arrangement of parts, an example of which is given in this specification and illustrated in the accompanying drawings, wherein:—

30. Figure 1 is a vertical sectional view of the device.

Fig. 2 shows a plan view of the gearing employed.

35. Figs. 3 and 4 show plan and side views, respectively, of a bearing block employed.

Fig. 5 shows a perspective view of an engaging jaw employed, and

Figs. 6 and 7 show plan and side views, respectively, of a clutch member employed.

40. Referring now more particularly to the drawings the numeral 1 refers to the drive stem which works through the stuffing boxes 2 and 3, the former of which is located in the upper end of the tubular nipple 4 and the latter of which is located in the lower end of the tubular nipple 5. The nipple 4 is connected to the lower end of the pipe 6 by means of the collar 7, and the nipple 5 is connected, by left hand threads, to the

45. depending neck 8 of the internal spur gear 9. The nipple 4 is splined on the stem 1 and is capable of vertical movement relative thereto. A coupling 10 is fitted over the lower end of the nipple 5 loosely and is retained thereon by means of an annular

flange 11 on which the internal annular shoulder 12 of the coupling rests. The lower end of this coupling is screwed, with left hand threads, onto the tubular section 13 which carries a fishing tool, (not shown) of 60 any conventional form. Underneath the neck 8 there is a collar 14 fastened on the nipple 5 and there is a coil spring 15 which surrounds said nipple and is interposed between the collar 14 and the coupling 10. 65 Above this coupling there is a key 16, carried by said nipple, which is adapted to move into a keyway 17 of the coupling 10 when the nipple moves downwardly through the coupling. 70

The internal gear 9 works in the bearing 18 whose lower end is formed with a retaining flange 19 whereon said gear rests and the lower end of the anchor block 20 is reduced and threaded into the upper end of the bearing 18. The upper end of the anchor block has a deep recess 21 and threaded onto the reduced upper end of said block there is a tubular casing 22 whose upper end is closed by means of a gland 23 which surrounds the 80 nipple 4 and is threaded into said casing. This gland is formed with internal spaced projections 24 adapted to, at times, mesh with similar projections 25 carried by the nipple 4 to form a clutch. 85

The lower end of the nipple 4 has an annular shoulder 26 and the upper end of the frusto conical block 27 is reduced and formed with an annular groove 28. The block 27 is suspended from the nipple 4 by means of an 90 anchor 29. This anchor is tubular and is formed of two sections to make its assembly possible and it has the upper and lower internal annular flanges 30, 31, the former of which engages over the shoulder 26 and the latter of which fits into the groove 28. The block 27 fits into the recess 21 and has a plurality of vertical dovetailed peripheral grooves 32 in which the dovetailed jaws 33 are adapted to slide. These jaws work 95 through aligned slots 34 cut through the walls of the recess 21, and engage with the well casing 38. 100

Splined on the stem 1 there is a spur gear 35 which is in mesh with a plurality of similar gears 36 whose shafts have upper bearings in the lower end of the anchor block 20 and lower bearings in the bearing plate 37. The gears 36 are in mesh with the internal gear 9 and when the stem is rotated 110

the gear 9 and the nipple 5 carried thereby will rotate in the reverse direction.

The device is assembled as shown in Fig. 1 and let down into the well bore until the fishing tool contacts with the pipe to be pulled. The spring 15 will be compressed by the weight sustained by it, thus minimizing the shock. The downward movement of the pipe section 13 and coupling 10 being arrested the key 16 will move into the keyway 17 and said coupling and pipe section 13 will be forced to rotate with the nipple 5. If the stem 1 is rotated forwardly, that is, in a clockwise direction, the pipe section 13, 15 and the fishing tool carried thereby, will rotate in the opposite direction. This fishing tool used in unscrewing the joints of the pipe to be withdrawn is usually a conical shaped tap having left hand threads and as 20 it is so rotated it will screw into the upper end of the pipe section to be unscrewed and engage therewith and unscrew the same and it may be then withdrawn. While unscrewing the pipe the anchor block 20 and 25 its appendants are held stationary by the jaws 33.

If it is desired to rotate the fishing tool forwardly, for any purpose, as for example to disengage it from the pipe to be pulled, 30 the pipe 6 may be pulled upwardly to bring the projections 24 and 25 into clutching position. This upward pull on the pipe 6 will cause the corresponding elevation of the block 27, the jaws 33 moving downwardly 35 and inwardly, to release the casing, and the entire device may then be rotated forwardly with the result sought to be obtained, as above specified, or withdrawn from the bore.

What we claim is:—

40 1. A device of the character described, including a driving member, a driven member, an anchor, means carried by the anchor whereby the device is fixed in a well casing, means carried by the anchor and operatively 45 connected with the driving member and the driven member, through which the rotation of the driving member will be imparted, in a reverse direction, to the driven member, a tubular member depending from the 50 driven member and arranged to be clutched therewith and declutched therefrom.

2. A device of the character described, including a driving member, a driven member, an anchor, means carried by the anchor

whereby the device is fixed in a well casing, 55 means carried by the anchor and operatively connected with the driving member and the driven member, through which the rotation of the driving member will be imparted, in a reverse direction, to the driven member, a tubular member depending from the driven member and arranged to be clutched therewith and declutched therefrom, and a yieldable cushion interposed between said driven and tubular members. 60 65

3. In a device of the character described, an anchor for securing the device against rotation in a well casing, said anchor consisting of an anchor block, a bearing block movable vertically relative thereto, jaws carried 70 by said bearing block and normally in engagement with said casing, a driving member working through said blocks, a driven member depending from and rotatable relative to said anchor block and gearing operatively connecting the driving and driven members, through which the rotation of the driving member is imparted to the driven member in the opposite direction. 75

4. In a device of the character described, 80 an anchor block having a recess formed therein with slotted walls, a bearing block in said recess, jaws slidably connected to said bearing block and normally working through said slots into engagement with a 85 well casing, said slidable connection being formed to withdraw the jaws from the casing when the bearing block is elevated, means for elevating the bearing block, a driving member working through said 90 blocks, a driven member depending from and rotatable relative to the anchor block, an operative connection between said members, whereby the rotation of the former is imparted in a reverse direction to the latter, and a clutch for connecting said elevating means, when elevated, with said anchor block to prevent their independent rotation. 95

In testimony whereof we have signed our names to this specification in the presence of 100 two subscribing witnesses.
